UNITED STATES PATENT OFFICE.

JOHN EDWARD DOOLEY, OF FOND DU LAC, WISCONSIN.

MOLD OR CENTERING DEVICE.

No. 910,046.

Specification of Letters Patent.

Patented Jan. 19, 1909.

Application filed April 18, 1908. Serial No. 427,862.

To all whom it may concern:

Be it known that I, JOHN EDWARD DOOLEY, a citizen of the United States, residing at Fond du Lac, in the county of Fond du Lac and State of Wisconsin, have invented a new and useful Mold or Centering Device, of which the following is a specification.

This invention relates to molds or centering devices of that general class especially designed for use in the construction of culverts, arches, drains, sewers and similar hollow structures.

The object of the invention is to provide a mold or centering device capable of being quickly set up for use and which may be readily adjusted to permit the formation of culverts of different sizes and shapes.

A further object of the invention is to provide a centering device including an expandable shell having a threaded actuating rod disposed within the same and operatively connected with the shell through the medium of a plurality of radiating arms or links so that by adjusting the rod the arms may be actuated to contract the shell thereby to permit its removal from the culvert.

A further object is to form one terminal of the expandable shell with a sleeve or collar adapted to engage the end of an adjacent shell section whereby several of said sections may be united.

A further object is to provide improved means for locking the over-lapped ends of the yieldable shell in adjusted position.

A still further object of the invention is generally to improve this class of devices so as to increase their utility, durability and efficiency.

Further objects and advantages will appear in the following description, it being understood that various changes in form, proportions and minor details of construction may be resorted to within the scope of the appended claims.

In the accompanying drawings forming a part of this specification: Figure 1 is a longitudinal sectional view of a mold or centering device constructed in accordance with my invention. Fig. 2 is a transverse sectional view taken on the line 2—2 of Fig. 1.

Fig. 3 is a detail perspective view of a portion of one end of the expandable shell showing the construction of the locking device.

Fig. 4 is a vertical sectional view of the locking device.

Similar numerals of reference indicate corresponding parts in all of the figures of the drawings.

The improved mold forming the subject matter of the present invention includes a cylindrical body portion 5 preferably in the form of a longitudinally split shell the adjacent ends of which are over-lapped at 6 so as to allow for expansion and contraction of the shell when constructing sewers or culverts of different cross sectional diameters.

The interior walls of the shell are reinforced and strengthened by the provision of a plurality of spaced longitudinally disposed bars 8 preferably in the form of angle irons, as shown, and each having one terminal thereof spaced from the adjacent end of the shell to produce a smooth interior surface 9 extending around the entire circumference of the shell. The opposite ends 70 of the angle bars 8 are offset at 10 and extended longitudinally beyond the adjacent end of the shell to form a support for a terminal coupling collar or sleeve 11. The sleeve or collar 11 is interposed between the offset portion of the bars 10 and the interior walls of the shell 5, said collar being rigidly secured to the shell and split transversely so as to permit the same to expand and contract with the shell.

Disposed within the shell 5 are longitudinal rod sections 12 and 13 united by a suitable coupling member 14 and each provided with right and left hand threads, as shown, there being correspondingly threaded collars 90 15 slidably mounted on the rod sections and provided with laterally extending ears 16. The collars 15 are operatively connected with

the interior of the shell through the medium of radiating arms or links 17 one end of 95 each of which is pivotally connected to the adjacent ear 16 while the opposite end thereof is pivotally connected at 19 with the lateral flange 20 of the angle bars, as shown. The outer end of the rod section 13 is provided with a hand wheel 21 so that by rotating the wheel the arms or links 17 may be actuated to effect the expansion and contraction of the shell.

The over-lapped ends of the shell 5 are 105 provided with interlocking teeth 21', the latter being preferably formed by cutting or severing the metal comprising the shell and then pressing the metal at the cut or severed portion thereof laterally in the direction of 110

the center of the shell, as best shown in Figs. 3 and 4 of the drawings.

It will thus be seen that the arms or links 17 support the shell in extended position so as to prevent the shell from collapsing by the weight of the cement when forming a culvert, drain, sewer or similar hollow structure, the inclined walls 22 of the teeth permitting the same to slide over each other 10 when the wheel 21 is actuated to contract the shell to permit removal of the latter from the molded structure.

In operation the teeth are disengaged and the shell expanded to produce a centering device of the desired transverse diameter 15 after which the wheel 21 is operated to further expand the shell, which additional expansion causes the teeth to interengage and thus lock the shell in adjusted or expanded 20 position. A mating shell is then placed in position on the collar 11 with the smooth inner face 9 of the inner shell engaging the outer face of the collar, as best shown in Fig. 1 of the drawing. The cement, concrete or 25 other plastic material is then positioned around the shell and troweled off in the usual manner. When the cement or concrete has thoroughly set the mold or centering device is withdrawn from the culvert by 30 turning the wheel 21 in the opposite direction which causes the arms or links 17 to contract the shell, the inclined faces 22 of the teeth 21' permitting the over-lapping ends of the expandible shell to pass each other 35 when the shell is contracted, as will be readily understood. Attention is here called to the fact that the interlocking teeth serve to support the overlapped edges of the expandible shell in engagement with each other 40 when introducing the shell within an excavation designed to receive the same and also serve to prevent lateral spreading of said edges when applying cement or other plastic material to the exterior walls of the shell.

45 If desired, the depressions or openings formed in the shell 5 by the teeth 21' may be filled with suitable blocks or plastic material preparatory to surrounding the shell with concrete so as to present a smooth uninterrupted surface to the concrete and thus prevent the formation of any hollows or projections in the inner walls of the completed culvert or other structure. It will also be understood that the expandible shells may be 55 made in different lengths and may be of elliptical, rectangular or other cross sectional formation.

Having thus described the invention what is claimed is:

60 1. A mold including an expandible shell, means disposed within the shell and operatively connected with the latter for contracting the shell, and means independent of the contractible means for locking the shell in contracted position.

2. A mold including an expandible shell, means disposed within the shell for contracting the same, a collar secured to and projecting longitudinally beyond one end of the shell and adapted to form a circumferential support for the end of a mating shell, and means independent of the contractible means for locking the shell in contracted position. 70

3. A mold including an expandible shell, longitudinal reinforcing bars secured to the interior walls of the shell and each having one end thereof terminating short of the adjacent end of the shell, the opposite ends of the reinforcing bars being off set and projected longitudinally beyond the opposite end of the shell, an expandible collar interposed between the shell at the off set portion of the bars, and an actuating member disposed within the shell and operatively connected with the reinforcing bars for contracting the shell. 75 80 85

4. A mold including an expandible shell, longitudinal reinforcing bars secured to the interior walls of the shell and provided with inwardly extending flanges, an actuating rod disposed within the shell and provided with right and left hand threads, collars engaging the threads on the rod and provided with ears, links forming a pivotal connection between the ears and the flanges of the reinforcing bars, a hand wheel for rotating the rod to effect the contraction of the shell, and means independent of the rod for locking the shell in contracted position. 90 95 100

5. A mold including a longitudinally split shell having its adjacent ends over-lapped and provided with interlocking teeth, and means disposed within the shell and operatively connected with the interior walls 105 thereof for contracting the shell.

6. A mold including a longitudinally split expandible tube having its adjacent ends over-lapped and provided with interlocking teeth, bars secured to the interior walls of the shell and provided with off set portions extending longitudinally beyond one end of said shell, and a coupling collar interposed between the off set portions of the bars and the interior wall of the shell and adapted 110 to engage the interior wall of a mating shell when two or more shells are coupled, and an actuating member arranged within the shell and operatively connected with the bars for effecting the contraction of the shell. 115 120

7. A mold including a longitudinally split expandible shell having its adjacent longitudinal edges over-lapped, the over-lapped edges of the shell being cut or severed and the metal at the cut or severed portion thereof being bent inwardly to form inclined teeth, angle bars secured to the interior walls of the shell and each having one end thereof off set and extended longitudinally beyond the adjacent end of the shell, a collar sup- 130

ported by the extended ends of the angle bars, an actuating rod extending longitudinally within the shell, and links forming a pivotal connection between the actuating rod and angle bars for effecting the contraction and expansion of the shell.

5 In testimony that I claim the foregoing

as my own, I have hereto affixed my signature in the presence of two witnesses.

JOHN EDWARD DOOLEY.
